UNITED STATES PATENT OFFICE.

CHARLES A. HENNICK, OF BUFFALO, NEW YORK, ASSIGNOR TO PRATT
& LETCHWORTH COMPANY, OF BUFFALO, NEW YORK.

SPRING-GEAR FOR VEHICLES.

No. 809,946.

Specification of Letters Patent.

Patented Jan. 16, 1906.

Application filed January 12, 1905. Serial No. 240,730.

To all whom it may concern:

Be it known that I, CHARLES A. HENNICK, a citizen of the United States, residing at Buffalo, in the county of Erie and State of New York, have invented a new and useful Improvement in Spring-Gears for Vehicles, of which the following is a specification.

This invention relates to spring-gears for vehicles of the side-spring type, in which the front bolster and rear axle are connected by longitudinal springs which are located at opposite sides of and support the body. In vehicles of this character no reaches are employed and the side springs, and in some instances a center longitudinal spring, form the only connection between the bolster and the rear axle and there is a tendency for the gear to be thrown out of rectangular form into the form of a rhomboid on account of the twisting and wrenching of the rear axle in rough usage.

The object of the invention is to produce a strong light frame of mechanical and economical construction for firmly connecting the box and its supporting-springs and holding the springs in their proper relation.

In the accompanying drawings, Figure 1 is a plan view of a spring-gear embodying the invention, one of the side springs being partially broken away to disclose the connecting-frame. Fig. 2 is a fragmentary section, on an enlarged scale, through one side spring and one side of the connecting-frame in line 2 2, Fig. 1. Fig. 3 is a transverse section, on an enlarged scale, in line 3 3, Fig. 1, also showing the connection of the frame with the vehicle-body. Fig. 4 is a perspective view, on an enlarged scale, of one of the angle-pieces of the connecting-frame. Fig. 5 is a detail section showing a different connection between the center spring and connecting-frame.

Like letters of reference refer to like parts in the several figures.

A and B represent, respectively, the rear axle and front bolster, C the longitudinal side springs, which are located at the sides of the body or box and are connected at opposite ends to the front bolster and rear axle, and C' the center spring, which is located between the side springs beneath the box and is connected at opposite ends to the rear axle and king-bolt or front bolster. The springs are parallel, and preferably the outer or side springs are composed of several superposed

leaves, while the center spring consists of a single flat spring-bar.

The connecting-frame is arranged substantially midway between the ends of the springs and is of rectangular form, consisting of four connected angle or corner pieces D, each having a longitudinal arm d extending lengthwise of and beneath one of the side springs and a transverse arm d' extending inwardly toward the center spring. The arms of each corner-piece are preferably connected by a diagonal brace d''. The adjacent ends of the longitudinal arms of the two angle-pieces D at one side of the gear are overlapped and connected together and to the side spring by the bolt e, which connects the several leaves of the spring. The end of the longitudinal arm of one of the angle-pieces at each side of the gear is offset or depressed, as shown at e', Fig. 2, so that the longitudinal arms will bear throughout nearly their full length against the under side of the spring. The two longitudinal arms d beneath each side spring are also attached to the spring by ordinary U-clips f, located at opposite sides of the bolt e. The inner ends of the transverse arms of the angle-pieces are rigidly attached in pairs to the center spring C—for instance, as shown in Fig. 3—by springing the ends apart, so that one extends above and one below the center spring, and passing bolts g through the lapped ends on opposite sides of the spring. Another way for attaching the transverse arms to the center spring is shown in Fig. 5, in which the ends of the arms are shown as lapped beneath the spring and attached to the latter by an ordinary U-clip g', straddling the spring.

The body or box H of the vehicle (shown in Fig. 3 and indicated by broken lines in Fig. 1) rests on and is secured to the rectangular connecting-frame by bolts h, passing through the side sills of the box and through bolt-holes h' provided therefor in the transverse arms of the angle-pieces D. One of the angle-pieces at each side of the gear preferably has a lateral extension i, which projects outwardly beyond the side spring and serves as a wear-iron to prevent the front wheels of the vehicle from striking and cutting the side springs.

The connecting-frame, consisting of the separate angle-pieces D, can be made economically of malleable iron, whereas a single-piece

frame of similar shape and weight is not feasible, owing to the practical difficulties in casting. It is also lighter and cheaper than a single-piece wrought-metal frame. As the frame is attached at three points to each side spring and has no joints at or near its angles, the side springs cannot shift longitudinally relative to each other, twisting the gear from a rectangular into a rhomboidal form, as they can in constructions in which the joints are made at or near the angles of the frame. While the frame is made of separate parts, it will be noted that no more attaching devices are required to connect the parts together and to the side and center springs than would be necessary with a single-piece unjointed frame. A further and important advantage of the construction is that angle-pieces of one size can be used for gears of different widths. The transverse arms d' are made long enough for the widest gear and in applying to the vehicle it is only necessary for the workman to lay off the proper distance between the bolt-holes h' for the box-securing bolts and the center spring and drill the holes in the inner ends of the transverse arms d' for the center spring bolts or clips.

The gear is probably stronger when the frame is attached to the center spring; but a center spring is not essential to the rigidity of the frame, and the latter makes a desirable connection between the side springs where no center spring is employed, provided the ends of the transverse arms are attached in pairs to each other.

I claim as my invention—

1. A connecting-frame for the side springs of vehicle-spring gears, comprising four angle-shaped corner-pieces having longitudinal arms which extend substantially parallel with and are connected to the side springs, and transverse arms which extend inwardly from the longitudinal arms, the inner ends of the transverse arms of opposite corner-pieces

being secured together substantially midway between the side springs, substantially as set forth.

2. A connecting-frame for the side springs of vehicle-spring gears, comprising four corner-pieces, each having a longitudinally-extending arm and a transversely-extending arm, the ends of the longitudinal arms of the pieces at each side of the gear overlapping and being secured together and to the side spring, and the inner ends of the transverse arms of opposite corner-pieces overlapping and being secured together substantially midway between the side springs, substantially as set forth.

3. A connecting-frame for the springs of vehicle-gears having side springs and a center longitudinal member, comprising four angle-pieces having longitudinal arms which extend substantially parallel with and are attached to the side springs, and transverse arms which extend toward and terminate substantially at said center member of the gear, the inner ends of the transverse arms of the corner-pieces being secured to said center member of the gear, substantially as set forth.

4. In a vehicle-spring gear, the combination of side springs, and a connecting-frame comprising four angle-shaped corner-pieces having longitudinal arms which extend substantially parallel with and are connected to the side springs, and transverse arms which extend inwardly from the longitudinal arms, the inner ends of the transverse arms of opposite corner-pieces being secured together substantially midway between the side springs, substantially as set forth.

Witness my hand this 31st day of December, 1904.

CHARLES A. HENNICKE.
